ELECTRIC DUST PRECIPITATOR

John J. Osmar, West Palm Beach, Fla.

Application August 4, 1952, Serial No. 302,536

6 Claims. (Cl. 183—7)

This invention relates to a dust collector.

An object of this invention is to provide a dust collector which embodies means for setting up electric discharge impulses which will effect the deposit of dust particles on a collector.

Another object of this invention is to provide a dust collector embodying a tubular duct with a suction fan at one end of the duct and a pair of electrodes within the duct which produce an electrical flux whereby dust particles in the air circulating through the tube will be deposited onto a collector sheet which is positioned across the tube.

A further object of this invention is to produce an electric circuit of relatively high voltage with a pair of confronting electrodes which are spaced apart a distance such as to eliminate any sparks being produced and at the same time develop an electrical flux whereby dust particles will be caused to bombard one of the electrodes or a collector disposed in front of said one electrode.

A further object of this invention is to provide an electrical dust collecting means embodying a pair of spaced electrodes wherein one electrode is very small in size and the other electrode is substantially large in size so that a conical electrical flux will be formed, and any dust particles adjacent the electrodes will be sucked into the electrical field or flux and will be bombarded onto a collector where the particles will be retained.

With the above and other objects in view, my invention consists in the arrangement, combination and details of construction disclosed in the drawing and specification, and then more particularly pointed out in the appended claims.

In the drawing:

Figure 1 is a horizontal section of a dust collecting machine constructed according to an embodiment of this invention showing diagrammatically the electric circuits embodied in this invention.

Figure 2 is a diagrammatic view showing the main electric circuit embodied in this invention.

Figure 3 is a sectional view taken on the line 3—3 of Figure 1.

Referring to the drawing, the numeral 10 designates generally a housing which is formed of front and rear walls 11 and 12, respectively, opposite side walls 13 and 14, with the latter formed as a closure. Side wall 14 includes inwardly projecting front and rear walls 15 and 16 which form a chambered closure which is hingedly secured, as at 17, to the rear wall 12.

A releasable catch or fastening means 18 is adapted to secure the closure 14 in closed position. It will, of course, be understood that the housing 10 embodies top and bottom walls (not shown) so as to form a completely enclosed housing. A horizontally disposed tube 19 extends through and between the front and rear walls 11 and 12, and a flanged bushing 20 is interposed between the front wall 11 and the forward or intake end of the tube 19. A similar flanged bushing 21 is interposed between the rear end of the tube 19 and the rear wall 12.

2

A pair of electrodes 22 and 23 are disposed substantially centrally of the length of the tube 19 and in the axial center thereof with electrodes 22 and 23 spaced apart a sufficient distance so that when these electrodes are connected with a source of electric energy, there will not be any spark or sparks jumping between the electrodes.

A partition wall 24 is secured between the front and rear walls 11 and 12 and divides a portion of the housing 10 into a transformer chamber 25. A transformer 26 of the step-up type is disposed in the chamber 25 and includes a secondary 27, which is connected by conductors 28 and 29 to terminals 30 and 31, respectively. The terminals 30 and 31 are disposed at the end of the housing 10 adjacent the closure 14, and a conductor 32 connects terminal 30 with electrode 22; whereas a conductor 33 connects terminal 31 with electrode 23.

The transformer 26 also includes a primary 34 which is connected by means of a conductor 35 to a terminal 36 of a connector socket 37. A fuse 38 is interposed in conductor 35 and conductor 35 includes an extension 39 which is connected to one side of a light 40 disposed within the housing 19. The terminal socket or connector 37 includes a second terminal 41 with which one end of a conductor 42 is connected and conductor 42 is connected to a switch 43.

The switch 43 is a main switch and a conductor 44 is connected to a normally closed spring-pressed switch 46. The switch 46 includes a spring-pressed button 47, which is adapted to be engaged by an angle member 48 carried by the flange 15 so that switch 46 will be disposed in closed position when closure 14 is in opened position. The other side of switch 46 is connected by means of a conductor 49 to a conductor 50, which is connected with the other end of the primary 34. An auxiliary switch 51 is connected at one side thereof by means of a conductor 52 to terminal or contact 45 of switch 43, and switch 51 includes a contact 53 which is connected by means of a conductor 54 to a terminal 55 of a connector socket 56.

Connector socket 56 includes a second terminal 57 which is connected by means of a conductor 58 to conductor 35. A pilot light 59 is connected across conductors 35 and 49 by means of conductors 60 and 61. A suction fan 62 is mounted at the discharge end of tube 19, being secured on an annular flange 63 by fastening members 64. Flange 63 is carried by the bushing 21.

The fan 62 includes an aperture sleeve 65 having a plurality of apertures 66 through which air is adapted to be discharged by means of a suction fan blade 67. The fan 62 is connected with connector socket 56 by means of a double wire conduit 68. Preferably, the electrode 23 is of frustocconical configuration with the base or large end thereof confronting the electrode 22, and electrode 23 is slidably on a horizontally disposed guide 69 and is constantly urged forwardly by means of a spring 70.

The forward or inner end of the electrode 23 may have a cap or plate 71 mounted thereon which is adapted to be disposed in contacting relation with a sheet or plate 72, which is inserted transversely across the tube 19 through slots 73 and 74, which are formed in the tube 19. The sheet 72 may be paper, thin cardboard or the like. One face of the sheet or collector 72 is adapted to confront the small electrode 22 and, as shown in Figures 1 and 2, the energizing of the transformer 26 will produce a conical electrical field or flux, indicated at 75, which extends from electrode 22 to the collector sheet 72. This electrical field will cause a bombardment of the collector 72 by the dust particles which are drawn into the tube 19 by the suction caused partly by the suction fan blade 67 and partly by the suction force created by the electrical field 75.

The core 76 of transformer 26 is adapted to be connected with a ground connector socket 77 by means of a conductor 78.

In the use and operation of this device, the connector 37 is connected to a source of electric current supply and after sheet or collector 72 is extended across the tube 19 and closure 14 has been opened, switches 43 and 51 may be closed. Switch 43 will energize transformer 26 and switch 51 will effect operation of suction fan 62. Suction fan 62 will cause a draft of air to move through tube 19 from the left to the right, as viewed in Figure 1, and inasmuch as the energizing of the electrodes 22 and 23 will produce the electrical field 75, any dust particles in the air stream moving through tube 19 will be bombarded onto the collector 72 for adherence to the latter.

This dust collector is particularly desirable for use in the operating rooms of hospitals or in other enclosures where it is desired to have the air as free from dust as is possible.

I do not mean to confine myself to the exact details of construction herein disclosed, but claim all variations falling within the purview of the appended claims.

What is claimed is:

1. A dust collector or precipitator comprising a tubular duct having a pair of opposed open ends, a pair of axially aligned electrodes disposed in said duct in spaced apart relation, means connecting said electrodes in an electric circuit, a sheet extending transversely across said duct between said electrodes, the width of said sheet being less than the inner diameter of said duct, guide means disposed in said duct for one of said electrodes, said one electrode being mounted for reciprocation on said guide means, and resilient means carried by said guide means and engaging said one electrode to constantly bias said one electrode for movement in abutting relation with respect to said sheet.

2. A dust collector or precipitator comprising a tubular duct having a pair of opposed open ends, a pair of axially aligned electrodes disposed in said duct in spaced apart relation, a sheet extending transversely across said duct between said electrodes, the width of said sheet being less than the inner diameter of said duct, one of said electrodes being imperforate and of frusto-conical configuration with the large end thereof confronting the other of said electrodes, said other of said electrodes having its said confronting end of smaller area than the area of said large end of said one electrode, means connecting said electrodes in an electric circuit, guide means disposed in said duct for said one of said electrodes, said one electrode being mounted for reciprocation on said guide means, and resilient means carried by said guide means and engaging said one electrode to constantly bias said one electrode for movement in abutting relation with respect to said sheet.

3. A dust collector or precipitator comprising a tubular duct open at each end, a pair of axially aligned electrodes disposed in said duct in spaced apart relation, one of said electrodes being imperforate and of frusto-conical configuration with the large end confronting the other of said electrodes, said other of said electrodes having its said confronting end of smaller area than said large end of said one electrode, said electrodes each having dimensions smaller than the diameter of said duct, means connecting said electrodes in an electric circuit, said duct having transversely aligned slots, a collector sheet extending through said slots, guide means disposed in said duct for said one electrode, said one electrode being mounted for reciprocation on said guide means, and resilient means

carried by said guide means and engaging said one electrode to constantly bias said one electrode for movement in abutting relation toward said sheet.

5. A dust collector or precipitator comprising a tubular duct open at each end, a pair of axially aligned electrodes disposed in said duct in spaced apart relation, one of said electrodes being imperforate and of frusto-conical configuration with the large end thereof confronting the other of said electrodes, said other of said electrodes having its said confronting end of smaller area than said large end of said one electrode, said electrodes each having dimensions smaller than the diameter of said duct, means connecting said electrodes in an electric circuit, said duct having transversely aligned slots, a collector sheet extending through said slots, guide means disposed in said duct for said one of said electrodes, said one electrode being mounted for reciprocation on said guide means, resilient means carried by said guide means and engaging said one electrode to constantly bias said one electrode for movement thereof to bring said large end of said one electrode into abutting relation with respect to said sheet, and a suction fan at one end of said duct.

10. A dust collector or precipitator comprising a tubular duct open at each end, a pair of axially aligned electrodes disposed in said duct in spaced apart relation, one of said electrodes being imperforate and of frusto-conical configuration with the large end facing the other of said electrodes, a guide member supported on said duct and extending therein, means slidably mounting said one electrode on said guide member, said electrodes each having dimensions smaller than the diameter of said duct, means connecting said electrodes in an electric circuit, said duct having transversely aligned slots, a collector sheet extending through said slots in contact with said frusto-conical electrode, and means on said guide member biasing said one electrode for movement toward said collector sheet.

15. A dust collector or precipitator comprising a tubular duct open at each of its respective ends, a pair of axially aligned electrodes disposed in said duct in spaced apart relation, one of said electrodes being imperforate and of frusto-conical configuration with the large end thereof confronting the other of said electrodes, a guide member supported on said duct and extending therein, means slidably mounting said one electrode on said guide member, said electrodes each having dimensions smaller than the diameter of said duct, means connecting said electrodes in an electric circuit, said duct having transversely aligned slots, a collector sheet extending through said slots in contact with said frusto-conical electrode, means on said guide member biasing said one electrode for movement toward said collector sheet, and a suction fan at one end of said duct.
